Inventor,

Carlos D. Hoppes
by Percy B. Hills
Attorney

UNITED STATES PATENT OFFICE.

CARLOS D. HOPPES, OF ASHLAND, OHIO, ASSIGNOR TO THE FAULTLESS RUBBER COMPANY, OF ASHLAND, OHIO, A CORPORATION OF OHIO.

BALL.

Application filed May 18, 1921. Serial No. 470,567.

To all whom it may concern:

Be it known that I, CARLOS D. HOPPES, a citizen of the United States, residing at Ashland, county of Ashland, State of Ohio, have invented certain new and useful Improvements in Balls, of which the following is a specification.

My invention relates to balls, and has for its object to provide an improved article 10 of manufacture of this character presenting a smooth surface of high finish. This object I accomplish in the manner and by the means hereinafter described and claimed, reference being had to the accompanying 15 drawing, in which:—

Figure 1 is an elevation of a ball made in accordance with my invention, a portion of the finishing patch thereon being shown turned back.

20 Figure 2 is a similar view of the ball in the process of construction, the cover being shown torn and turned back to show the interior ball.

25 Figure 3 is a detail perspective view of a conventional toy balloon which may be used in the manufacture of my improved article.

Figure 4 is an enlarged fragmentary sectional view of a portion of a ball made in accordance with my invention.

30 Figure 5 is an elevation, partly broken away, of a slightly modified construction.

Similar numerals of reference denote corresponding parts in the several views.

In the said drawing, referring more particularly to Figures 1 to 4, the reference numeral 1 denotes a solid ball, formed preferably of rubber in the usual manner. The ball is first dipped in self-curing rubber cement 3, then a flexible cover, such as a 35 toy balloon 4, is stretched over it by means of a suitable spreader, the cement causing the cover to adhere firmly to the surface of the ball, as readily will be understood. When this is done the neck 5 of the cover

40 may be cut off in such manner that that portion of the cover at the base of said neck can be brought together substantially to cover completely the surface of the underlying ball 1, or at least to leave but a narrow 45 slit, as shown at 6 in Figure 1. In order to conceal this slit portion of the cover, the

same may be overlaid with a patch, preferably composed of rubber, of any desired shape, said patch being shown in Figure 1 at 7 in the form of a star, which patch not 55 only will serve to conceal the slit 6, but will present an ornamental appearance, it being understood that said patch is made of extremely thin material.

In Figure 5 I have shown a slightly modified construction, the interior ball 8 being hollow instead of solid, and being enveloped by a cover 4 as in the Figure 2 construction. In place of the star patch 7 shown in Figure 1, I have illustrated a circular patch 9, 65 covering the slit 6. It will be understood that the cover 4 may be of any desired color, and if preferred, the patches applied thereto may be of contrasting color.

While I prefer to form the interior ball 70 1 of rubber, I do not wish to be understood as limiting the invention in this particular, as said ball may be formed of any other suitable material, and may be solid, as shown in Figure 1, hollow as shown in Figure 5, 75 or formed of semi-solid material, such as sponge rubber.

I have shown and described a toy rubber balloon as the preferred article for use as the cover, but I do not wish to be understood 80 as limiting the invention to this article, as the cover may be made especially for this purpose, the prerequisites being that it shall be sufficiently elastic to permit its being stretched over the ball, and provided with 85 an aperture for this purpose, the edges of which may, when the cover has been placed on the ball, be brought substantially together, as hereinbefore described.

Having thus fully described my invention, 90 what I claim as new and desire to secure by Letters Patent, is:—

1. An article of manufacture, comprising a ball, and a covering of pre-vulcanized thin rubber stretched thereover. 95

2. An article of manufacture, comprising a ball, and a covering of pre-vulcanized thin rubber stretched thereover and cemented thereto.

3. An article of manufacture, comprising 100 a ball, and a pre-vulcanized rubber cover stretched thereover and cemented thereto,

the edges of the opening in said cover being drawn together substantially to close the aperture at that point.

4. An article of manufacture, comprising a ball, a pre-vulcanized rubber cover stretched thereover and cemented thereto, the edges of the opening in said cover being

drawn together substantially to close the aperture at that point, and a patch of thin material disposed over said drawn edges to conceal the same.

In testimony whereof I hereunto affix my signature.

CARLOS D. HOPPES.
